(57) **CLAIM**

The ornamental design for a building blocks toy set, as shown and described.

DESCRIPTION

FIG. 1 is a perspective view of a first toy of the building blocks toys toy set in accordance with the design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a second toy of the building blocks toy set;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a perspective view of a third toy of the building blocks toy set;

FIG. 16 is a front elevational view thereof;

FIG. 17 is a rear elevational view thereof;

FIG. 18 is a left side elevational view thereof;

FIG. 19 is a right side elevational view thereof;

FIG. 20 is a top plan view thereof;

FIG. 21 is a bottom plan view thereof;

FIG. 22 is a perspective view of a fourth toy of the building blocks toy set;

FIG. 23 is a front elevational view thereof;

FIG. 24 is a rear elevational view thereof;

FIG. 25 is a left side elevational view thereof;

FIG. 26 is a right side elevational view thereof;

FIG. 27 is a top plan view thereof;

FIG. 28 is a bottom plan view thereof;

(Continued)

FIG. 29 is a perspective view of a fifth toy of the building blocks toy set;
 FIG. 30 is a front elevational view thereof;
 FIG. 31 is a rear elevational view thereof;
 FIG. 32 is a left side elevational view thereof;
 FIG. 33 is a right side elevational view thereof;
 FIG. 34 is a top plan view thereof;
 FIG. 35 is a bottom plan view thereof;
 FIG. 36 is a perspective view of a sixth toy of the building blocks toy set;
 FIG. 37 is a front elevational view thereof;
 FIG. 38 is a rear elevational view thereof;
 FIG. 39 is a left side elevational view thereof;
 FIG. 40 is a right side elevational view thereof;
 FIG. 41 is a top plan view thereof;
 FIG. 42 is a bottom plan view thereof;
 FIG. 43 is a perspective view of a seventh toy of the building blocks toy set;
 FIG. 44 is a front elevational view thereof;
 FIG. 45 is a rear elevational view thereof;
 FIG. 46 is a left side elevational view thereof;
 FIG. 47 is a right side elevational view thereof;
 FIG. 48 is a top plan view thereof;
 FIG. 49 is a bottom plan view thereof;
 FIG. 50 is a perspective view of an eighth toy of the building blocks toy set;
 FIG. 51 is a front elevational view thereof;
 FIG. 52 is a rear elevational view thereof;
 FIG. 53 is a left side elevational view thereof;
 FIG. 54 is a right side elevational view thereof;
 FIG. 55 is a top plan view thereof;
 FIG. 56 is a bottom plan view thereof;
 FIG. 57 is a perspective view of a ninth toy of the building blocks toy set;
 FIG. 58 is a front elevational view thereof;
 FIG. 59 is a rear elevational view thereof;
 FIG. 60 is a left side elevational view thereof;
 FIG. 61 is a right side elevational view thereof;
 FIG. 62 is a top plan view thereof;
 FIG. 63 is a bottom plan view thereof;
 FIG. 64 is a perspective view of a tenth toy of the building blocks toy set;
 FIG. 65 is a front elevational view thereof;
 FIG. 66 is a rear elevational view thereof;
 FIG. 67 is a left side elevational view thereof;

FIG. 68 is a right side elevational view thereof;
 FIG. 69 is a top plan view thereof;
 FIG. 70 is a bottom plan view thereof; and,
 FIG. 71 is a perspective view of the building blocks toy set in a combined and stacked state.
